UNITED STATES PATENT OFFICE.

CHARLES ERNEST DAWSON, OF TEDDINGTON, ENGLAND.

APPARATUS FOR PRODUCING AN EXPLOSIVE OR COMBUSTIBLE MIXTURE OF LIQUID FUEL AND AIR.

1,029,796.

Specification of Letters Patent. Patented June 18, 1912.

Application filed March 5, 1912. Serial No. 681,796.

To all whom it may concern:

Be it known that I, CHARLES ERNEST DAWSON, a subject of the King of Great Britain, and resident of 3 Ferry road, Teddington, in the county of Middlesex, England, mechanical engineer, have invented certain new and useful Improvements in Apparatus for Producing an Explosive or Combustible Mixture of Liquid Fuel and Air, 10 of which the following is a specification.

This invention relates to carbureters, that is to say, apparatus for producing an explosive or combustible mixture of liquid fuel and air, and it has for its object to enable 15 increased flexibility in working to be obtained by enabling the composition of the mixture to be instantly varied in accordance with changes in the conditions of working.

For the purpose of the present invention 20 the fuel is admitted through a central nozzle to the atomizing and mixing chamber concentrically with a stream of heated air which is caused by a primary mixing cone or cones of the usual character to impinge 25 upon the stream of fuel so as to produce therewith what may be termed the primary mixture, while additional supplies of air are admitted to the chamber through lateral ports; concentrically arranged annular 30 baffles of conical form being employed to 35 control the course of the mixture during its passage through the chamber.

According to the present invention the atomizing and mixing chamber is provided, 35 in advance of the primary mixing cone or cones, with successive annular baffles of substantially conoidal form, arranged concentrically with the fuel nozzle and mixing cone or cones and projecting inward from the 40 wall of the chamber in a direction opposed 45 to that of the main or central stream which issues from the primary mixing cone or cones; these annular baffles being adapted to cause centripetal or convergent currents of air, admitted through lateral ports provided 50 in the wall of the chamber, to impinge upon the main or central stream in a direction normal or contrary to that of the flow of 55 said stream, in such manner as to prevent contact of the fuel with the walls of the chamber until the condition of a substantially permanent gas has been attained.

The atomizing and mixing chamber is 55 cylindrical, and the admission of air through the lateral ports in the wall of the chamber

is regulable at will by means of a rotary valve-sleeve concentric with the chamber and adapted to control the port openings, while the admission of fuel to the atomizing nozzle is concurrently controlled by a valve so 60 geared to said rotary valve-sleeve that the quantity of fuel admitted will be increased or diminished according as the air-inlet ports are opened more or less widely.

In the accompanying drawings Figure 1 65 is a vertical section through one form of carbureter for an internal combustion engine, constructed according to the invention. Fig. 2 is a like view of a slightly modified form.

Referring first more particularly to Fig. 70 1, the cylindrical outer casing *a* of the atomizing and mixing chamber is screwed on to a flange upstanding from a plate *b* constituting an extension of the bottom of a 75 float chamber *c*. In this plate *b* is drilled a 80 passage *d* terminating at one end in the jet *e* 85 and at the other end in the float chamber. The jet *e* is surrounded by a nozzle *f* which 90 constitutes the primary mixing cone and to 95 which the pipe *g* leads through a passage in the plate *b*. Within the casing *a* fits a lining *h* adapted to be turned by a lever *i* and having segmental slots *k* which, when the lining 100 is in a certain position, register with like 105 slots *k*¹ in the casing. The extent of the opening afforded by the slots *k*¹ may be adjusted by turning the sleeve *a*¹ relatively to the casing *a*, the sleeve being provided with similar slots. A pipe *l* opens from the upper 110 part of the casing and a similar opening in the lining registers with this pipe when the 115 slots *k* and *k*¹ are in register with one another; the pipe *l* leads to the intake of the 120 engine.

Preferably there are three upper slots 125 *k*, *k*¹, and three lower slots *l*, *l*¹, equally 130 spaced around the lining and casing, so that when the lining *h* is turned through an angle of (say) 60° the slots and the pipe *l* 135 are all closed, the lining thus serving at the 140 same time as the throttle valve and as the 145 valve for controlling the slots or ports *k*¹. Obviously, in intermediate positions of the 150 lever *i* the pipe *l* and ports *k*¹ are more or 155 less open.

For the purpose of controlling the supply 160 of fuel at the same time as the supply of air, the lining *h* has cut in its outer surface an annular rack *m* which is in gear with a 165 pinion *n* mounted on the spindle *o* of the 170

needle-valve that closes the passage *d*. Instead of being cut on the outer surface of the lining *h*, the annular rack may be fixed to the top of the carbureter, as shown in Fig. 2, and, together with the pinion *n*, this rack may be readily changed when it is desired to alter the ratio of the gear. When the lever *i* is turned, the needle-valve spindle *o* is rotated on its axis, and by means of the screw thread *o*¹ closes or opens the passage *d* more or less.

Within the lining *h* is fixed the liner *p*, which is so shaped as to present in succession the downwardly directed truncated cones *p*¹ which constitute the annular baffles for intermixing the air admitted through the respective sets of ports *k* with the air and vapor issuing from the nozzle *f*, an annular baffle *p*¹ being provided in connection with each set of ports *k*. The central openings presented by successive baffles should increase progressively in diameter, and should be suitably proportioned to the areas of the nozzles *f* and pipe *l*, respectively, while the first or lowest baffle should be adapted to cause the centripetal currents of air, admitted through the corresponding ports *k*, to impinge upon the main or central stream (which issues from the mixing cone *f*) in direction approximately normal to that of said stream, the subsequent baffle or baffles being adapted to cause the centripetal currents of air respectively controlled by them to impinge in a direction substantially the reverse of that of the central stream. To bring about these results, first baffle *p*¹ nearest to the nozzle *f* is provided with a convex operative surface which is adapted to direct the currents of air entering through the respective ports *k* downwardly and horizontally to impinge on the main or vapor carrying stream at substantially right angles; while the second baffle *p*¹ is provided with a concave operative surface which is adapted to direct the air currents entering through its ports *k* inwardly and downwardly so as to meet or oppose the vapor carrying stream; the action of the two baffles being such as to thoroughly intermix the air and vapor and insure a substantially permanent and uniform gas mixture.

The drawings show two sets of ports *k* and baffles *p*¹, but more than two sets of such ports and baffles may be used.

For limiting the minimum opening of the throttle, there may be an adjustable stop, such as the screw *h*¹ (Fig. 2) working in a lug *h*² of the cover *h*³ and adapted to strike against a bracket *a*² carried by the casing *a*.

The float chamber is connected with the oil-reservoir through the pipe *g* which is controlled by the spring-urged ball *r* in the usual manner.

The air drawn through the pipe *g* is heated in a known manner by the exhaust of the engine or otherwise, and if it should be found desirable to adjust the temperature of this air without varying the source of heat, an externally opening port *g*¹ in the pipe *g* may be controlled by a rotatable sleeve *g*².

Claims:

1. In a carbureter, the combination of a chamber having an outlet near one end, a jet for delivering liquid fuel centrally into said chamber near the opposite end thereof, a convergent nozzle for delivering heated air into the chamber around and in advance of said jet, a series of annular baffles projecting in succession inward from the wall of the chamber in advance of and concentrically with said nozzle and each having the form of a hollow truncated cone whose diameter increases in the direction of the flow of fluid through the chamber, said chamber being provided with annular series of lateral air-inlets for coacting with the respective annular baffles and each situated in advance of the central opening of the corresponding baffle. 75

2. In a carbureter, the combination of a chamber having an outlet near one end, a jet for delivering liquid fuel centrally into said chamber near the opposite end thereof, a convergent nozzle for delivering heated air into the chamber around and in advance of said jet, an annular baffle projecting inward from the wall of the chamber in advance of and concentrically with said nozzle, said annular baffle being in the form of a hollow truncated cone whose diameter increases in the direction of the flow of fluid through the chamber and having the profile of its operative surface convexly curved, a similar annular baffle situated in advance of the first mentioned baffle but having the profile of its operative surface concavely curved, said chamber being provided with annular series of lateral air-inlets for coacting with the respective annular baffles, each series being situated in advance of the central opening of the corresponding baffle. 95

3. In a carbureter, the combination of a chamber having an outlet near one end, a jet for delivering liquid fuel into said chamber near the opposite end thereof, a convergent nozzle for delivering heated air into the chamber around and in advance of said jet, a series of annular baffles projecting in succession inward from the wall of the chamber in advance of and concentrically with said nozzle and each having the form of a hollow truncated cone whose diameter increases in the direction of the flow of fluid through the chamber, said chamber being provided with annular series of lateral air-inlets for coacting with the respective annular baffles. 100

110

115

120

125

130

nular baffles and each situated in advance of the central opening of the corresponding baffle, and means for regulating the effective area of said air-inlets.

5. 4. In a carbureter, the combination of a chamber having an outlet near one end, a jet for delivering liquid fuel into said chamber near the opposite end thereof, a convergent nozzle for delivering heated air into the chamber around and in advance of said jet, a series of annular baffles projecting in succession inward from the walls of the chamber in advance of and concentrically with said nozzle and each having the form 70
10 of a hollow truncated cone whose diameter increases in the direction of the flow of fluid through the chamber, said chamber being provided with annular series of lateral air-inlets for coacting with the respective 75
15 annular baffles and each situated in advance of the lateral opening of the corresponding baffle, and means for concurrently varying the effective area of said air-inlets and the 80
20 quantity of liquid fuel delivered through 85
25 the aforesaid jet.

5. In a carbureter, the combination of a chamber having an outlet near one end, a jet for delivering liquid fuel into said chamber near the opposite end thereof, a convergent 90
30 nozzle for delivering heated air into the chamber around and in advance of said jet, a series of annular baffles projecting in succession inward from the wall of the chamber in advance of and concentrically 95
35 with said nozzle and each having the form of a hollow truncated cone whose diameter increases in the direction of the flow of fluid through the chamber, said chamber being provided with annular series of lateral air- 100
40 inlets for coacting with the respective annular baffles and each situated in advance of the central opening of the corresponding baffle, and means for concurrently varying the effective area of said air inlets and of 105
45 the outlet from the chamber and also the quantity of liquid fuel delivered through the aforesaid jet.

6. In a carbureter, the combination of a cylindrical chamber having an outlet near 110
50 one end, a jet for delivering liquid fuel centrally into said chamber near the opposite end thereof, a convergent nozzle for delivering heated air into the chamber around and in advance of said jet, a series of annular 115
55 baffles projecting in succession inward from the wall of the chamber in advance of said nozzle and each having the form of a truncated cone whose diameter increases in the direction of the flow of fluid through the 120
60 cylindrical chamber, said chamber being provided with annular series of lateral air-inlets for coacting with the respective annular baffles and each situated in advance of the central opening of the corresponding baffle, and a sleeve rotatable concentrically 125
65

and in contact with the wall of the cylindrical chamber and provided with series of apertures severally adapted to register with the openings of the respective annular series of lateral air-inlets.

7. In a carbureter, the combination with a source of liquid fuel supply, of a cylindrical chamber having an outlet near one end, a duct leading from the source of fuel supply into said chamber, a valve on said duct for controlling the passage of liquid fuel therethrough, a stationary nut, a rotary screw-threaded spindle engaging said nut for regulating the opening afforded by said valve, a jet forming the termination of said duct within the cylindrical chamber near the end thereof opposite to the lateral outlet, a passage for delivering heated air into the cylindrical chamber, a nozzle forming the termination of said passage within said chamber and shaped as a hollow truncated cone convergent about and in advance of the fuel-supply jet, a series of annular baffles projecting in succession inward from the wall of the cylindrical chamber in advance of said nozzle and each having the form of a hollow truncated cone whose diameter increases in the direction of the advance of fluid through the chamber, lateral air-inlets in communication with the interior of said chamber for coacting with the respective annular baffles, the delivery apertures of the respective air-inlets being presented in annular series in the wall of the cylindrical chamber in advance of the central openings of the corresponding annular baffles, a sleeve rotatable concentrically and in contact with the wall of the cylindrical chamber and provided with annular series of apertures severally adapted to register with the delivery apertures of the respective lateral air-inlets, and gearing interposed between said sleeve and the aforesaid screw-threaded spindle.

8. In a carbureter, the combination with a source of liquid fuel supply, of a cylindrical chamber having a lateral outlet near one end, a duct leading from the source of liquid fuel supply into said chamber, a valve on said duct for controlling the passage of liquid fuel therethrough, a stationary nut, a rotary screw-threaded spindle engaging said nut for regulating the opening afforded by said valve, a jet forming the termination of said duct within the cylindrical chamber near the end thereof opposite to the lateral outlet, a passage for delivering heated air into the cylindrical chamber, a nozzle forming the termination of said passage within said chamber and shaped as a hollow truncated cone convergent about and in advance of the fuel-supply jet, a series of annular baffles projecting in succession inward from the wall of the cylindrical chamber in advance of said nozzle and each having the form of a hollow truncated cone whose di- 130

- ameter increases in the direction of the advance of fluid through the chamber, lateral air-inlets in communication with the interior of said chamber for coacting with the respective annular baffles, the delivery apertures of the respective air-inlets being presented in annular series in the wall of the cylindrical chamber in advance of the central openings of the corresponding annular baffles, a sleeve rotatable concentrically and in contact with the wall of the cylindrical chamber and provided with annular series of apertures severally adapted to register with the delivery apertures of the respective lateral air-inlets, gearing interposed between said sleeve and the aforesaid screw-threaded spindle, and a port in the wall of said sleeve so situated as to be adapted to register with the lateral outlet of the cylindrical chamber
- 20 when the apertures in said sleeve register with the delivery openings of the lateral air-inlets in the wall of said chamber.
9. In a carbureter, the combination with a source of liquid fuel supply, of a cylindrical chamber having a lateral outlet near one end, a duct leading from the source of liquid supply into said chamber, a valve on said duct for controlling the passage of liquid fuel therethrough, a stationary nut, a rotary screw-threaded spindle engaging said nut for regulating the opening afforded by said valve, a jet forming the termination of said duct within the cylindrical chamber near the end thereof opposite to the lateral outlet, a passage for delivering heated air into the cylindrical chamber, a nozzle forming the termination of said passage within said chamber

and shaped as a hollow truncated cone convergent about and in advance of the fuel-supply jet, a series of annular baffles projecting in succession inward from the walls of the cylindrical chamber in advance of said nozzle and each having the form of a hollow truncated cone whose diameter increases in the direction of the advance of fluid through the chamber, lateral air-inlets in communication with the interior of said chamber for coacting with the respective annular baffles, the delivery apertures of the respective air-inlets being presented in annular series in the wall of the cylindrical chamber in advance of the central openings of the corresponding annular baffles, a sleeve rotatable concentrically and in contact with the wall of the cylindrical chamber and provided with annular series of apertures severally adapted to register with the delivery apertures of the respective lateral air-inlets, gearing interposed between said sleeve and the aforesaid screw-threaded spindle, a port in the wall of said sleeve so situated as to be adapted to register with the lateral outlet of the cylindrical chamber when the apertures in said sleeve register with the delivery openings of the lateral air-inlets in the wall of said chamber, and means for adjusting the maximum effective area of said apertures in the sleeve and of the delivery openings of said lateral air-inlets.
